UNITED STATES PATENT OFFICE

ANDREW J. KILE, OF HARRISONBURG, VIRGINIA.

INCUBATOR-REGULATOR.

1,276,543.

Specification of Letters Patent. Patented Aug. 20, 1918.

Application filed July 13, 1917. Serial No. 180,389.

To all whom it may concern:

Be it known that I, ANDREW J. KILE, a citizen of the United States, residing at Harrisonburg, in the county of Rockingham and 5 State of Virginia, have invented certain new and useful Improvements in Incubator-Regulators, of which the following is a specification.

This invention relates to an improved 10 regulator for incubators and has as its primary object to provide a construction employing complementary regulating levers which will be simultaneously actuated from a thermostat therefor.

15 The invention has as a further object to provide a construction wherein the thermostat will be connected with each of the said levers and to also provide an improved connection between the levers so that the said 20 levers will be caused to pivot simultaneously.

A still further object of the invention is to provide one of the levers with an improved connecting member or pivot loop 25 of such nature that one or more auxiliary regulating levers may all be engaged with the said loop to be simultaneously actuated by the thermostat.

30 And the invention has as a still further object to provide an arrangement wherein the lever arm of the thermostat will be so connected thereto that the said arm may be easily and quickly removed, should the arm become broken or its efficiency otherwise impaired to necessitate the repair of the arm.

35 Other and incidental objects will appear as the description proceeds and in the drawings wherein I have illustrated the preferred embodiment of the invention and wherein similar reference characters designate corresponding parts throughout the several views:

40 Figure 1 is a side elevation partly broken away and showing my improved regulator in connection with a conventional type of incubator.

45 Fig. 2 is a detail perspective view showing the improved connection employed between the complementary regulating levers,

50 Fig. 3 is a perspective view showing a conventional type of incubator equipped with an auxiliary regulating lever and illustrating the manner in which the said lever is connected with the complementary levers

of the regulator to be actuated simultaneously therewith, and

55 Fig. 4 is a fragmentary sectional view particularly illustrating the detachable mounting of the lever arm of the thermostat of the regulator.

60 In order that the construction, mounting and operation of my improved regulator may be accurately understood I have, in Fig. 1 of the drawings, shown the device in connection with a conventional type of incubator 10 provided with an egg chamber 11 and equipped with a lamp flue 12 from the lamp casing 13 of the incubator. In carrying out the invention I employ complementary lever stands 14 which are mounted upon the top of the incubator in any approved manner. One of these stands is shown in detail in Fig. 2. Mounted upon the said stands are coacting regulating levers 15 and 16 respectively. These levers 70 include fulcrum members 17 and 18 respectively through which extend rods 19 engaged through ears 20 upon the stands 14 and pivotally connecting the said members with the stands. As particularly shown in 75 Fig. 1, the levers 15 and 16 each include a long arm and a short arm. For convenience, the shorter arms of the said levers have been indicated at 21 and 22 respectively. Connected to the longer arm of the lever 15 80 is a damper 23 arranged to close a suitable vent flue from the egg chamber 11 of the incubator. The longer arm of the lever 16 is equipped with a similar damper 24 arranged to close the lamp flue 12.

85 The shorter arm 21 of the lever 15 is preferably formed from a length of suitable resilient wire bent intermediate its ends to provide a pivot loop or connecting member 25. From the said loop, the free extremity 90 of the said length of wire is again bent upwardly and then rearwardly to form a counterpoise supporting arm or bracket 26 extending over the said loop. Adjustable longitudinally upon the said bracket is a 100 counterpoise 27. At its outer end, the shorter arm 22 of the lever 16 is slotted to provide a fork 28 freely engaging with the loop 25. Thus, this loop serves to pivotally connect the levers 15 and 16 to both be 105 balanced by the single counterpoise 27.

Connected in any approved manner with the stands 14 are spaced tubular posts 29

projecting into the egg chamber 11 and connected at their lower ends by a cross bar 30 to form a supporting frame for the thermostat. Mounted upon the said bar is 5 a thermostat 31 preferably formed of co-acting wafers. Projecting from one side of the thermostat is a stud 32 threaded through the bar 30 for detachably connecting the thermostat with the said bar. Projecting from the opposite side of the thermostat is a similar stud 33. Screw threaded upon the stud 33 is a cross head 34 which is thus detachably connected with the thermostat. At its extremities, the cross head 15 34 is given a half turn and is provided with suitable openings. Detachably engaging through these openings are connecting rods 35 which extend within the posts 29 of the supporting frame for the thermostat and 20 project through the fulcrum members 17 of the levers 15 and 16. Screw threaded upon the upper extremities of the said rods are adjusting nuts 36.

As will now be readily understood, the 25 thermostat 31 will, of course, expand as the temperature of the egg chamber 11 rises. Expansion of the said thermostat will move the cross head 34 downwardly and accordingly simultaneously pivot the regulating levers 14 and 15 to raise the dampers 23 and 24. Since the levers are pivotally connected at their inner ends, the said levers will always move in unison and by adjusting the nuts 36, the temperature at which 35 the dampers 23 and 24 shall be raised, may be easily varied.

It will therefore be seen that I provide a 40 particularly simple and efficient construction for the purpose set forth. In this connection, particular attention is directed to the fact that should the cross head 34 of the thermostat become broken or its efficiency otherwise impaired, the connecting rods 35 may be disengaged from the said 45 cross head when the cross head may be detached by simply unscrewing it from the post 33 of the thermostat. This provides a convenient arrangement whereby the cross head may be quickly renewed or repaired.

50 In Fig. 3 of the drawings, I have illustrated the manner in which an auxiliary regulating lever may be employed as a part of my improved regulator. In this figure an incubator has been conventionally shown at 37. 55 Mounted upon the top wall of the incubator are the lever stands 14' carrying the regulating levers 15' and 16' connected at their inner ends by the pivot loop 25'. The dampers 23' and 24' of these levers are respectively arranged to close a vent flue leading to each of the egg chambers of the incubator. The stands 14', levers 15' and 16' and pivot loop 25' as well as the dampers 23' and 24' are identical with corresponding elements of the 60 preferred construction. Suitably located

upon the top wall of the incubator is a lever stand 38 identical with the stands 14' and carrying a regulating lever 39 which is a counterpart of the levers 15' and 16'. The longer arm of this lever 39 is equipped with a damper 70 40 arranged to close the lamp flue 41 of the incubator. The shorter arm 42 of the said lever is formed in a manner similar to the shorter arm of the lever 16' and is provided with a fork 43 engaging the pivot loop 25' 75 of the lever 15'. The pivot loop 25' will thus connect all of the said levers for simultaneous movement so that when the thermostat within the incubator expands, the three dampers 23', 24' and 40 will be lifted. It 80 will therefore be seen that the connecting loop 25' provides a simple and convenient arrangement whereby one or more auxiliary regulating levers may be connected with the levers 15' and 16' to be actuated simultaneously therewith so that the device may thus be used upon incubators having several different vent flues, for regulating the incubator from a single thermostat.

Having thus described the invention, what 90 is claimed as new is:

1. A device of the character described including regulating levers, means pivotally connecting the inner extremities of the said levers, a counterweight carried by the inner 95 extremity of one of the levers for balancing both of the said levers, and a thermostat operatively connected with the levers for simultaneously actuating the said levers.

2. A device of the character described including regulating levers, the inner extremity of one of said levers being formed to provide an elongated pivot member and thence extended to provide a counterpoise supporting arm, means carried by the inner 100 extremity of the other of the levers and freely engaging the pivot member for pivotally connecting the said levers, a counterpoise mounted upon said arm for balancing both of the levers, and a thermostat operatively connected with the levers for simultaneously actuating the said levers.

3. A device of the character described including regulating levers, the inner extremity of one of said levers being bent to form a pivot loop and thence again bent from the said loop to form a counterpoise supporting arm, means carried by the inner extremity of the other of said levers and freely engaging said loop for pivotally connecting the 115 levers, a counterpoise mounted upon said arm for balancing both of the levers, and a thermostat operatively connected with the levers for simultaneously actuating the said levers.

4. A device of the character described including regulating levers, means pivotally connecting the inner extremities of the said levers, a frame associated with the levers, a thermostat mounted upon the said frame,

a cross head connected with the said thermostat and free at its extremities, and connecting means between the extremities of said cross head and the said regulating levers respectively.

5. A device of the character described including regulating levers, a frame associated therewith, a thermostat mounted upon the said frame, a cross head connected to the 10 said thermostat and carried thereby, and means operatively connecting the said cross head with the said regulating levers.

6. A device of the character described including regulating levers, a frame associated 15 therewith, a thermostat mounted upon the said frame, a stud extending from the thermostat, a cross head connected with said stud, and an operative connection between the extremities of the cross head and the 20 said regulating levers respectively.

7. A device of the character described including regulating levers, a pivot loop carried by the inner extremity of one of said levers, a fork carried by the inner extremity 25 of the other of said levers and adapted to freely engage the said loop at different points thereon for pivotally connecting the levers, and a thermostat operatively connected with the levers for actuating the said 30 levers.

8. A device of the character described including regulating levers, mountings for the levers pivotally supporting the said levers for movement in one plane, means carried by the inner extremity of one of the levers 35 and pivotally engaged by the inner extremity of the other of said levers for pivotally connecting the said levers, the said means being formed for engagement by the inner extremity of the said second mentioned lever 40 in various dispositions of the lever mountings to support the levers in angular relation to each other in a different plane, and a thermostat operatively connected with the levers for actuating the said levers. 45

9. A device of the character described including a regulating lever, a second regulating lever, a circular loop carried by the inner extremity of the first lever and pivotally engaged by the inner extremity of the second lever for pivotally connecting the said levers, the said loop being adapted for operative engagement by the inner extremities of a plurality of levers extending radially from the loop for pivotally connecting all of such levers with the first lever, and a thermostat operatively connected with the levers for actuating the said levers. 50 55

In testimony whereof I affix my signature.
ANDREW J. KILE. [L.S.]
